[57] CLAIM

The ornamental design for a frozen dessert, as shown and described.

DESCRIPTION

FIG. 1 is a top plan view of a frozen dessert showing my new design;

FIG. 2 is a side elevational view thereof, the undislosed sides being substantially the same; and

FIG. 3 is a top perspective view thereof.

The bottom is plain and unornamented.
